UNITED STATES PATENT OFFICE.

GEORGE ALBERT LYON, OF PHILADELPHIA, PENNSYLVANIA.

VEHICLE BUFFER DEVICE.

1,420,855.

Specification of Letters Patent. Patented June 27, 1922.

Application filed June 10, 1921, Serial No. 476,584. Renewed May 15, 1922. Serial No. 561,166.

To all whom it may concern:

Be it known that I, GEORGE ALBERT LYON, a citizen of the United States, and resident of Philadelphia, county of Philadelphia, 5 State of Pennsylvania, have made a certain new and useful Invention Relating to Vehicle Buffer Devices, of which the following is a specification, taken in connection with the accompanying drawing, which forms 10 part of the same.

This invention which is a continuation in part of that disclosed in my copending application Serial No. 424,685 filed November 17, 1920, relates especially to resilient buffer 15 or bumper devices for automobiles or other vehicles in which the spring steel or other resilient strips or members have clamped thereto, a resilient sheet metal or other contact clamping device having a vertically 20 wide contact face throughout the central part of the buffer, and preferably having integral clamping members to adjustably or otherwise clamp thereto the buffer front strips. Such vertically extending clamping 25 devices may be advantageously formed of spring steel strip or sheet metal three sixteenths to five sixteenths of an inch thick more or less, and having if desired vertically separated contact portions, one of 30 which may be substantially in line with the buffer front strips one or more of which may extend across the buffer front behind or adjacent the cooperating contact clamping member. These different front contact 35 portions may be separated from each other vertically to the desired extent, so as to secure a front collision face which may be substantially flat if desired, and which may have a vertical width of six or eight inches more 40 or less in some cases. With the present type automobiles in which the front frame members are arranged quite close to the ground, it is often desirable to have this collision contact face extend upward more than downward 45 with respect to the buffer front strip or member, and any of these types of clamping contact devices may if desired be formed with integrally stamped or formed clamping members thereon, which may more or 50 less fit around or enclose the cooperating front strip so as to have considerable aligning action with respect thereto. In many cases it is desirable to form this spring steel or other contact clamping member with a 55 polished nickel plate finish, so as to have a desirable appearance when secured upon the

black finished or other spring steel strip buffer members with which it may be used.

In the accompanying drawing showing in a somewhat diagrammatic way various illustrative embodiments of the invention, 60

Fig. 1 is a perspective view of one form of buffer.

Fig. 2 is a transverse vertical section taken substantially along the line 2—2 of Fig. 1. 65

Fig. 3 is a corresponding section taken along the line 3—3.

Fig. 4 is a perspective view of another construction; and

Fig. 5 is a detail vertical section taken 70 along the line 5—5 of Fig. 4.

The automobile buffer may have any desired or suitable construction and preferably comprises one or more pieces of spring steel strip which at the buffer front, may in some 75 cases be advantageously arranged in overlapping or reenforcing position. As is indicated in Fig. 1, a Lyon type spring buffer is shown comprising the attaching arm or member such as 1 connected with the end 80 loop 4 through the outwardly extending bend or curved portion 3. This spring steel strip may be extended inward from the end loop 4, so that this front strip 9 may extend across the buffer front and overlap the corresponding front strip 7 of the other spring 85 steel strip buffer member, which may have an end loop 6, curved portion 5 and attaching member 2.

Instead of or in addition to the usual 90 clamping devices, these buffer front strips or impact receiving members 7, 9, may be adjustably or otherwise connected by clamping members formed integrally if desired with the wide face contact member used to 95 reinforce and extend the buffer front. As shown in Fig. 1 this contact clamping member which may be formed of tempered spring steel or other suitable strong or resilient material, may have several vertically separated contact portions such as 11, 12, one of 100 which is preferably substantially in line with the clamping ends 14, 15 of this contact and clamping device, while the one or more vertically separated members such as 105 12 may be several inches away therefrom according to the particular conditions to be met. As shown in Figs. 2 and 3 this sheet metal contact and clamping device may be formed with integral clamping members adjacent its ends and also other portions if desired, and for this purpose, the spring steel 110

plate may be originally stamped out with tongues or projections which may be subsequently stamped or otherwise bent or formed into the enclosing clamping members 5 where the ends of these tongues 16, 20 are brought close together and perforated for the clamping bolt 19. In this way these horizontally separated clamping members may securely and rigidly clamp the buffer 10 front strips 7, 9 in adjusted position and some of these clamping members are preferably located on either side of the buffer front approximately in line with the separated attaching members 1, 2, which may be formed 15 on the buffer strip. This brings the clamping members adjacent the ends 8, 10 of these overlapping or reenforcing front strips which may if desired be substantially straight throughout this front connecting 20 portion. It is desirable to further strengthen or reenforce the contact clamping device by stamping or forming reenforcing stiffening ribs such as 18 thereon, and by forming these ribs on the upper edges 25 of the buffer, a pleasing appearance is given thereto as well as greatly strengthening the contact device under collision conditions. As above indicated, the amount of separation between the lower edge 15 of the 30 upper contact portion and the adjacent part of the lower portion 11 may be several inches or more, and in many cases it may be at least as great a vertical separation as the width of the buffer strip which is usually 35 about two to two and one half inches in the standard Lyon bumpers.

Fig. 4 shows another form of the device in which the contact clamping device used to 40 reenforce and enlarge the contact portion of the buffer front is formed with two vertically separated contact portions 22, 23, which in this instance are both vertically displaced from the end clamping portions 45 24, 25 of the device so as to be correspondingly out of line with the front strips 7, 9 of the buffer, one or both of which may advantageously extend across this clamping contact device. This clamping device is also in this instance, preferably formed of tempered 50 spring steel about a quarter of an inch or so thick, and may have reenforcing stiffening ribs such as 28 stamped or formed upon its edges where they do not interfere with the cooperating front strip of the 55 buffer. As indicated in Fig. 5, these adjacent reenforcing ribs may be arranged adjacent or in substantial contact with the edges of the buffer front strips, so as to assist in holding them in alignment although the 60 integral or other clamping devices which may be used at the ends of the contact device are in many cases sufficient for this purpose. Integral strips or ears on the contact plate may be stamped or forced around into the position indicated in Fig. 5 in which the

clamping strip 27 is substantially behind the clamping end 24 of this front contact plate, while the other clamping strip 26 may have its end perforated, so that a clamping bolt 19 may pass through 70 these strip ends which are preferably though not necessarily arranged in the oblique position indicated. These horizontally separated integral clamping members 75 securely engage and hold the buffer front strips in position and strongly support the front contact plate therefrom, so that considerable increased stiffness and strength of the buffer front is thus secured as well as giving the buffer a pleasing appearance. 80 This buffer contact device may for example, be given a nickel finish and be used in connection with black enamel finish spring strip members.

This invention has been described in connection with a number of embodiments, forms, proportions, parts, arrangements, materials, methods of connection and use, to the details of which disclosure the invention is not of course to be limited, since 90 what is claimed as new and what is desired to be secured by Letters Patent is set forth in the appended claims:

1. The automobile buffer formed of spring steel strip and comprising attaching arms, 95 connected end loops and connected adjustably overlapping front strips, and a resilient sheet metal contact and clamping device formed with ribbed vertically separated contact portions and with integral enclosing 100 clamping members cooperating with said front strips substantially as far apart as said attaching members to adjustably and securely clamp said front strips and contact device together.

2. The automobile buffer formed of spring steel strip and comprising attaching arms, connected end loops and connected adjustably overlapping front strips, and a resilient sheet metal contact and clamping device 110 formed with vertically separated contact portions and clamping members cooperating with said front strips to adjustably and securely clamp said front strips and contact device together.

3. The automobile buffer formed of spring steel strip and comprising attaching arms, and connected overlapping front strips, and a resilient sheet metal contact and clamping device formed with ribbed 120 vertically separated contact portions having several times the vertical width of said strip and with integral enclosing horizontally separated clamping members to adjustably and securely clamp said front 125 strips and contact device together.

4. The automobile buffer formed of spring steel strip and comprising attaching arms and connected overlapping front strips, and a resilient sheet metal contact and 130

- clamping device formed with contact portions having several times the vertical width of said strip and with integral enclosing horizontally separated clamping members to clamp said front strips and contact device together. 5
5. The automobile buffer formed of spring steel strip and comprising attaching arms, connected end loops and overlapping front strips, and a resilient sheet metal contact and clamping device formed with ribbed vertically separated contact portions one of which is substantially in line with said front strips and the other 10 raised above them at least as much as the strip width and separated integral enclosing clamping members to adjustably and securely clamp said front strips and contact device together. 15
10. The spring steel contact and clamping device adapted for use with resilient front strip buffers and formed with ribbed vertically separated contact portions one of which is substantially in line with said front strip and the other vertically displaced therefrom at least as much as the 15 strip width and integral enclosing clamping members adapted to adjustably and securely clamp said contact device to said front strip. 20
11. The spring steel contact and clamping device adapted for use with resilient front strip buffers and formed with vertically separated contact portions one of which is substantially in line with said front strip and the other vertically displaced therefrom at least as much as the strip width and integral clamping members adapted to 25 adjustably and securely clamp said contact device to said front strip. 25
12. The spring steel contact and clamping device adapted for use with resilient front strip buffers and formed with vertically separated contact portions one of which is substantially in line with said front strip and the other vertically displaced therefrom and clamping members 30 adapted to adjustably and securely clamp said contact device to said front strip. 30
13. The resilient sheet metal vertically extending contact and clamping device 35 adapted for use with spring strip automobile buffers and comprising a relatively flat front collision face having vertically separated ribbed reinforced portions and integral clamping members substantially in line with one of said portions to engage and securely hold the buffer strips. 40
14. The resilient sheet metal vertically extending contact and clamping device adapted for use with spring strip automobile buffers and comprising a vertically wide collision face having vertically separated reinforced portions and integral clamping members substantially in line 45 with one of said portions to engage and securely hold the buffer strips. 50
55. The automobile buffer formed of spring steel strip and comprising end loops and connected front strip, and a contact
